PRESSURIZED SPRAY DISPENSER HEAD

Richard W. Ryan, Great Neck, N.Y.

Application December 24, 1958, Serial No. 53,894

Term of patent 14 years

(Cl. D62--2)

Figure 1 is a front elevational view of a pressurized spray dispenser head showing my new design.

Figure 2 is a right side elevational view thereof.

Figure 3 is a top plan view thereof.

Figure 4 is a bottom plan view thereof.

Fig. 5 is a front perspective view thereof.

Fig. 6 is a vertical sectional view taken longitudinally through the center of Fig. 3, on a reduced scale.

I claim:

The ornamental design for a pressurized spray dispenser head, as shown.
